UNITED STATES PATENT OFFICE.

JOHN F. HAUSSMANN, OF MILWAUKEE, WISCONSIN.

INTERNAL-COMBUSTION ENGINE.

1,402,494.

Specification of Letters Patent.

Patented Jan. 3, 1922.

Application filed June 22, 1920. Serial No. 390,712.

To all whom it may concern:

Be it known that I, JOHN F. HAUSSMANN, a citizen of the United States, and resident of Milwaukee, in the county of Milwaukee 5 and State of Wisconsin, have invented certain new and useful Improvements in Internal-Combustion Engines; and I do hereby declare that the following is a full, clear, and exact description thereof.

10 My invention relates to new and useful improvements in engines, and pertains particularly to internal combustion engines, employing ordinary commercial combustible fuels.

15 It is the primary object of this invention to provide an engine of this character having a pair of simultaneously operable pistons working in the same cylinder and driven by the same fuel explosions.

20 It is also an object of this invention to provide an internal combustion engine with means for preventing the parts stopping on dead center when the operation is discontinued.

25 A further object of the invention is to provide an engine having a pair of pistons operable at the same time in the same cylinder with means for connecting both of said pistons to a single crank shaft.

30 With these general objects in view, the invention resides in the novel features of construction, combination and arrangement of parts which will be hereinafter more particularly described and claimed.

35 In the accompanying drawing the figure represents a vertical longitudinal sectional view through an internal combustion engine embodying the principal features of my invention.

40 Referring more particularly to this illustration, it will be noticed that I have shown the invention in use on an upright engine having a base portion 1 on which a vertical cylinder 2 is secured. It will be obvious,

45 however, from the following description that in so far as the operation of the invention is concerned, the cylinder 2 might well be horizontally disposed. Consequently various changes may be made in the form

50 and proportions of the different parts of the invention without departing from the principles thereof or sacrificing any of its advantages.

In the type of engine shown, the lower 55 end of the cylinder 2 which is bolted to the base 1 is open, and likewise if desirable

the top may be open, the same having, however, a centrally positioned bearing 3 in which a piston rod 4 reciprocates. The piston 5 which is secured rigidly to this rod 60 4 forms the upper piston which is operable in the cylinder 2. A lower piston 6 is also longitudinally slidable within the cylinder 2.

In the base 1 is journalled a crank shaft 65 7 having a crank 8 with which the connecting rod 9 is connected. The upper end portion of the connecting rod 9 extends into the cylinder 2 and has a piston 6 pivoted thereto by means of a wrist pin 10. Obviously 70 the movement of the piston 6 within the cylinder 2 rotates the crank shaft 7 as is customary in similar engines.

Inasmuch as is necessary for the piston rod 4 to slide longitudinally of the cylinder 75 2, a somewhat different means is employed for connecting the same to the crank shaft 7. In other words a rocker arm 11 is pivoted to the upper or outer end of the piston rod, and to one end thereof a relatively long link 12 is pivoted, the lower 80 end of this link being similarly secured to one arm 13 of a bellcrank 14. The same is fulcrumed on a bracket ear 15 extending from one side of the base 1, and has its 85 other arm 16 connected with the connecting rod 9 by link 17. A pivot 18 is formed on the connecting rod 9 for the link 17 at a point spaced from the crank pin 19.

On the side of the base 1 opposite the 90 bracket ear 15 there is formed or secured a bracket arm 20, and a bellcrank 21 is fulcrumed thereto. One arm 22 of the bellcrank 21 is connected by link 23 with the longer portion of the rocker arm 11, whereas the 95 other arm 24 has a link 25 pivoted thereto. This link 25 like the link 17, is pivoted as at 18' to the connecting rod 9 at a point spaced from a crank pin 19.

As is customary in internal combustion 100 engines, the combustible fuel is admitted into the cylinder, and after being exploded by the aid of a spark plug or the like 26, the resulting exhaust gases are expelled through an outlet port controlled by a suitable valve. In the present drawing one of these control valves is illustrated and designated by the reference character 27. When a fuel charge has been compressed between the pistons 5 and 6 and is ignited by an 110 electric spark, the expansion thereof will force the said pistons away from each other

toward the opposite ends of the cylinder 2 and the crank shaft 7 rotated. Inasmuch as the charge of fuel is compressed by the heads of the pistons and is disposed in a combustion chamber formed by said heads, and the adjacent part of the cylinder wall, said pistons will be moved toward and away from each other substantially simultaneously. The full force of the explosion is thus spent on both of the piston heads. The several links and levers are so designed as to size and proportions and so assembled with respect to each other and to the piston rod 4 and crank shaft 7, that the parts cannot stop on dead center when the operation of the engine is discontinued. In other words, the relation of the various parts of the invention is such that one of the pistons will be at the start of its return or exhaust stroke just prior to the completion of the power stroke of the other piston.

I claim:

1. In an engine, a cylinder having inlet and outlet ports, a crank shaft, a pair of pistons in said cylinder, the same being simultaneously reciprocated by the power exerted by the same charge of motive fluid, a connecting rod between one of said pis-

tons and the crank shaft, a rigid piston rod secured to the other piston, a bellcrank pivoted on each side of the line of movement of the pistons, a link connecting one arm of each bellcrank with said crank shaft, and a link connecting the other arm of each bellcrank with said piston rod.

2. In an engine, a cylinder having inlet and outlet ports, a crank shaft, a pair of opposed piston heads in said cylinder, a connecting rod, pivotally connected at one end to one of said piston heads and journaled at the other end to the crank shaft, a piston rod rigidly secured to the other piston head, a rocker arm pivoted to the outer end of the rigid piston rod, a pair of bellcranks mounted on opposite sides of the cylinder, a link connection between one end of each bell crank and the journaled end of the connecting rod, and a link connection between the other end of each bellcrank and the corresponding end of the rocker arm.

In testimony that I claim the foregoing I have hereunto set my hand at Milwaukee, in the county of Milwaukee and State of Wisconsin.

JOHN F. HAUSSMANN.
